KELLY HANDLING DEVICE

William A. Pitts, Tulsa, Okla.

Application January 23, 1948, Serial No. 4,012

11 Claims. (Cl. 214—1)

1

The invention relates to kelly handling devices, and has for its object to provide a device of this kind, located adjacent one side of the derrick structure, and provided with means whereby the kelly may be intermittently received and stored in the handling device as drill string sections are run in or pulled, thereby obviating the present practice of storing the kelly in a rat hole, adjacent one side of the rotary table where it is in the way of operators on the derrick platform, thereby giving the workmen a clear platform in connecting and disconnecting drill string sections.

A further object is to provide a kelly receiving trackway pivotally mounted for movement in a vertical plane to one side of a derrick and provided with a carriage for the reception and guidance of the lower end of the kelly towards the outer end of the trackway and latching means for the trackway for holding the trackway in upward and inward inclined position when the full weight of the kelly is received thereon.

A further object is to provide a fluid actuated check member between the trackway and the base, and between the pivotal point of the trackway and the derrick for controlling the pivotal action of the trackway.

A further object is to provide the trackway carriage with a pivoted sleeve adapted to receive therein the lower end of the kelly when in a vertical position within the derrick structure, and to incline upwardly and inwardly as the kelly is lowered, and to move towards the outer end of the track as the kelly approaches the inclination of the track and rests thereon.

A further object is to provide the sleeve with means for maintaining the same upright for the reception of the lower end of the kelly when the sleeve is adjacent the inner end of the trackway.

With the above and other objects in view, the invention resides in the combination and arrangement of parts as hereinafter set forth, shown in the drawings, described and claimed, it being understood that changes in the precise embodiment of the invention may be made within the scope of what is claimed without departing from the spirit of the invention.

In the drawings:

Figure 1 is a side elevation of the handling device showing a part of the derrick and the kelly stored in the handling device.

Figure 2 is an enlarged vertical longitudinal sectional view through the outer end of the handling device showing the latching means.

Figure 3 is an enlarged detail sectional view

2

in perspective of the carriage and portion of the trackway.

Figure 4 is a vertical longitudinal sectional view through the carriage and a portion of the trackway showing the lower end of the kelly in the sleeve.

Figure 5 is a horizontal sectional view through the outer end of the trackway showing the carriage in the position it assumes at the outer end of the trackway.

Referring to the drawings, the numeral 1 designates a conventional form of derrick structure and 2 the platform. Heretofore kellys which are of considerable length have been stored in rat holes to one side of the rotary table, and the present device provides storage for the kelly to one side of the derrick out of the way of operators in running in additional string sections, or pulling the drill string.

Disposed to one side of the derrick 1 is a horizontal frame 3, which may rest on the ground, and extending upwardly from the frame 3 at a point spaced from its ends is an adjustable samsom post 4, on the upper end of which is pivoted at 5 the tiltable kelly receiving trackway 6. The inner end 7a of the trackway extends into the derrick structure and terminates spaced from the vertical center of the derrick, and at a substantial elevation above the platform 2, so workmen can easily walk under the same. The kelly receiving trackway 6 is formed from spaced channels 7 connected together by cross brackets 8. Secured within the channels 7 in engagement with their lower flanges 9 are wooden bars 10 on which the carriage 11 slides. The carriage 11 comprises side bars 12, the inner ends of which are provided with guide rollers 13 and slide shoes 14, which shoes slide on the wooden bars 10. The other ends of the side bars 12 have rockable connections on the trunnions 15 formed integral with the kelly receiving sleeve 16, and the trunnions 15 have formed, integral therewith arcuate slide members 17 which make a partial rotation as the carriage moves from the inner end of the trackway to the outer end thereof. The upper end of the sleeve 16 is flared as shown at 18 to receive the lower end 19 of the kelly 20 so that the threaded pin 21 of the kelly rests in the bottom of the sleeve 16 as shown in Figure 4.

To maintain the engagement between the lower end of the kelly and the carriage, the sleeve 16 is provided with oppositely disposed leaf springs 22 which extend through vertical slots 23 in the sleeve and frictionally engage the kelly, therefore it will be seen that, as the outer end of

the kelly and carriage move from the inner end of the trackway to the outer end of the trackway, as shown in dotted and full lines in Figure 1, this interengagement will be maintained.

Extending upwardly from the frame 3 at its outer ends are spaced members 24 having adjustably mounted therein a limit block 25, which limits the downward swing of the outer end of the trackway. In view of the fact that the upper swivel end of the kelly is heavier than its outer end, when at rest on the trackway, latching means is provided between the limit block and the outer end of the trackway. The latching means comprises a bumper 26 slidably mounted in a bearing 27 carried by the trackway, and this bumper is in the path of the end 28 of the sleeve 16. Disposed within the trackway around a latching shaft 29, carried by the bumper 26, is an expansion spring 30 which normally forces the bumper 26 and latching shaft 29 inwardly to inoperative position. When the kelly approaches the outer end of the trackway, the trackway swings downwardly into the limit block, and the weight of the kelly against the bumper 26 forces the latching shaft 29 into the aperture 31 of the limit block, as clearly shown in Figure 2.

The oscillation of the trackway is controlled in its upward and downward movement by a fluid controlled snubbing device 32, which may be of any construction desired, however it is provided with check valves 33 which control its speed of operation. This fluid controlled device may be controlled from any position desired.

At the starting of operation, the trackway is in the dotted line position, shown in Figure 1, with the sleeve 16 latched in vertical position by the latch spring 34 cooperating with the rest bracket 35 carried by the trackway, and at which time the carriage is in inner position. The lower end 19 of the kelly is inserted in the sleeve 16, and then the kelly is lowered towards the full line position. This will unlatch the carriage at 34, and it will move outwardly in the trackway, assuming the various dotted line positions shown in Figure 1, until it passes the pivotal position 5 and finally comes to rest in a longitudinal position on the trackway, as shown in full lines in Figure 1. It will be noted that the latching device 29 will maintain the trackway in the full line position, overcoming the heavier weight at the inner end of the kelly, involving the swivel 36. When it is again desired to use the kelly, the swivel hook 37 is connected to the bail 38 of the kelly and the kelly is raised, and during this raising operation the carriage within the trackway will move inwardly on the trackway, assuming the various dotted line positions shown in Figure 1, until the carriage passes the pivotal point 5 of the trackway, thereby overbalancing the trackway in favor of its inner end against the fluid controlled device 32 until the inner end of the trackway rests on the adjustable headache post 39, and at which time the trackway is in a horizontal position as shown in dotted lines in Figure 1, with the sleeve 16 in upright position for the next operation, however the fluid controlled device 32 will allow the inner end of the trackway to assume the full line position shown in Figure 1, out of the way of the workmen on the derrick platform 2, if desired.

From the above it will be seen that a handling device is provided for kellys, which is simple in construction, positive in its operation and one which will eliminate the storing of the kelly in the conventional rat hole now used, consequently

a free platform is provided for the operations of workmen.

The invention having been set forth what is claimed as new and useful is:

5. 1. A handling device adapted to be disposed adjacent a derrick structure and to receive thereon a kelly and move said kelly away from the center of the derrick and to the side of the derrick, said device comprising a hinged rockable platform having one of its ends extending into the derrick and its outer end extending away from the side of the derrick, said platform being mounted for rockable movement in a vertical longitudinal plane, a traveller carriage within 10 said platform and adapted to move from end to end of said platform across its hinged point, a kelly end receiving sleeve carried by said carriage and hingedly mounted thereon, means for rockably moving said platform on its hinged point in a vertical longitudinal plane whereby said carriage is moved to the outer end of the platform and the kelly deposited on the platform.
2. A device as set forth in claim 1 including 15 means for latching the outer end of the platform in down position after the kelly has been deposited on the platform.
3. A device as set forth in claim 1 including 20 a limit block adjacent the outer end of the platform when in down position, a latch carried by the end of the platform, a keeper carried by the limit block and with which the latch cooperates, said latch being operated by the engagement therewith of the carriage when in outer position.
4. A device as set forth in claim 1 including 25 a limit block at the outer end of the platform for limiting the downward movement of the outer end of the platform, a latch for latching the outer end of the platform and the limit block, said latch being operated by the engagement therewith of the carriage when it reaches the outer end portion of the platform.
45. 5. A device as set forth in claim 1 comprising a plunger latch member carried by the outer end of the platform in the path of the carriage, said plunger latch being normally forced inwardly and projected outwardly by the engagement therewith of the carriage, a limit block for limiting the downward swing of the outer end of the platform, said plunger latch cooperating with keeper means carried by the limit block.
6. A device as set forth in claim 1 including 50 a fluid controlled means cooperating with the under side of the inner end of the platform and forming means to govern the oscillation of the platform at various positions of the kelly on the platform.
65. 7. A device as set forth in claim 1 including a fluid controlled means carried by the kelly end receiving sleeve of the carriage for frictionally holding the carriage to the kelly end as the carriage traverses the platform.
8. A device as set forth in claim 1 wherein 70 the sleeve has its outer end flared, springs carried by opposite sides of the sleeve and extending through openings in the sleeve and adapted to frictionally grip a kelly end within the sleeve.
9. A device as set forth in claim 1 wherein 75 the carriage sleeve is provided with means for maintaining the same upright when it reaches the inner end of the platform.

10. A device as set forth in claim 1 wherein the platform is formed by opposed channeled members, said carriage being longitudinally movable in said channeled members.

11. A device as set forth in claim 1 wherein the carriage comprises side bars, said sleeve being pivotally mounted in one of the ends of each of said side bars, arcuate slide members carried by opposite sides of the sleeve and rockable with the sleeve, said side bars having bifurcated ends in which the cam members are mounted, the other ends of said bars being slidably supported through the medium of slide shoes and anti-fric-

tional rollers having their axes vertically disposed.
